UNITED STATES PATENT OFFICE.

JOHN R. SMITH, OF CLEVELAND, OHIO.

FABRIC BOLT BOARD.

Application filed July 28, 1922. Serial No. 578,123.

To all whom it may concern:

Be it known that I, JOHN R. SMITH, a citizen of the United States, residing at Cleveland, in the county of Cuyahoga and State of Ohio, have invented a certain new and useful Improvement in Fabric Bolt Boards, of which the following is a full, clear, and exact description, reference being had to the accompanying drawings.

10 This invention relates to fabric bolt boards such as are used in department stores for storing cloth and other textile fabrics on the shelves.

15 The principal objects of the present invention are to provide a fabric bolt board which shall present an exceptionally neat and attractive appearance and which shall be simple in construction, inexpensive to manufacture and highly durable in use; to provide 20 a fabric bolt board which shall include a simple and effective arrangement for obtaining samples of the fabric in minimum time and with minimum waste; to provide means for recording certain information regarding 25 the fabric on the bolt board, such information being plainly visible at all times and easily changed when desired, although normally protected from wear and soilure, while further objects and advantages will 30 appear as the description proceeds.

In the accompanying drawings wherein I have shown certain illustrative embodiments of my invention, Fig. 1 is a perspective view of one end of a fabric bolt board 35 constructed in accordance with my invention; Fig. 2 is a similar view showing the head removed from one end of the board and the cloth or other fabric also removed from the board; Fig. 3 is a longitudinal sectional view through the board; Fig. 4 is a 40 fragmentary vertical sectional view through one end of a modified form of bolt board, and Fig. 5 is an end elevation thereof.

Describing by reference characters the 45 various parts illustrated, 1 indicates the body portion of the board which is preferably of a light weight wood capable of receiving a smooth finish. Each end of this board is provided with a longitudinal recess 2 and a 50 reduced portion 3 defining a shoulder 4. Each reduced portion is adapted to receive a metal head 5 which is preferably of cast aluminum so as to be light in weight, and highly polished so as to present a neat and 55 attractive appearance. Each head 5 is in the form of a flattened cylinder which is

provided with diametrically arranged projecting plates 6, 6 which form the top and bottom walls of the recess 2 when the head is fastened to the board. A partition 7 is 60 disposed transversely of the head 5 and is preferably inset a slight distance from the front or outer edge of said head for a purpose to be referred to hereinafter. This partition is provided with an aperture 9 65 which is disposed in longitudinal alignment with recess 2 in the board and said partition is also provided with suitable apertures 10, for the reception of fastening screws (not shown) and buttons 11 for securing a 70 card 12 to said partition.

Each end of the board is fitted with a head 5 which abuts the shoulder 4 and lies flush with the body portion of the board. Suitable screws are inserted through apertures 10 and serve to fasten the head to said board. The fabric or cloth is wound on the board in the usual manner and a strip 15 about one to one and one-half inches wide is cut across the width of the cloth or 80 fabric. This strip is then rolled up and inserted through aperture 9 into recess 2 and the end thereof is then inserted up through a slot 14 formed in head 5 and the free end of the sample strip is then tucked 85 under one of the folds of cloth on the bolt board as clearly shown in Fig. 1. A card 12 is then snapped over buttons 11 and this card serves to close aperture 9 and also to display suitable information regarding 90 the cloth or fabric. When a sample of the cloth is desired it is only necessary for the clerk to cut off a suitable length from the sample strip 15 and replace the end under the folds as previously described. 95 When the sample strip is exhausted, a new strip may be cut and easily inserted in recess 2 by removing card 12. It is obvious that a great saving in cloth will result from use of my board as the present practice is 100 to cut a small sample from the cloth on the bolt board, and when the next customer purchases some of the cloth it is necessary to allow for the strip from which the sample was previously cut. It will also be noted 105 that the card 12 is inset in the head 5 and hence is protected from wear and soilure due to frequent handling of the bolt board.

In Figs. 4 and 5 I have shown a cylindrical fabric bolt board which is desirable 110 for rolling velvets and similar goods thereon. The body portion 1^a is preferably a wooden

cylinder which is provided with a longitudinal bore 2^a in each end. A cylindrical polished aluminum head 5^a is fastened to each end by screws 16. The partition 7^a is provided with an aperture 9^a so that the sample roll may be inserted therethrough and into bore 2^a. As shown at 17 in Fig. 4 and in dotted lines in Fig. 5, a portion of cylinder 1^a is recessed so that the end of 10 the sample strip may be inserted through a slot 14^a in head 5^a. A circular card may be fastened over suitable buttons 11^a projecting from partition 7^a to display the necessary information and close aperture 9^a. The use 15 of this board is similar to that previously described in connection with Figs. 1-3 inclusive.

Having thus described my invention what I claim is:

20 1. A fabric bolt board comprising a body portion having one end thereof reduced and provided with a recess, a head fitted to said reduced end and normally closing said recess, said head being provided with two 25 apertures communicating with said recess, one of said apertures being of sufficient size to permit insertion of a sample strip in said recess and the other of said apertures being in the form of a narrow slit to permit the 30 end of said strip to be inserted therethrough, and means normally closing the larger of said apertures.

2. A fabric bolt board comprising a body

portion having one end thereof reduced and provided with a recess, a head fitted to said 35 reduced end having a partition inset from the outer edge thereof, said partition having an aperture in alignment with said recess whereby a sample strip may be inserted within said recess, said head being provided 40 with a slit to permit the end of said sample strip to be inserted therethrough, and means for fastening a card to said partition to normally close said aperture.

3. A fabric bolt board comprising a body 45 portion having each end thereof reduced and provided with a longitudinal recess intermediate the side edges thereof, a metal head fitted to each reduced end portion and normally closing said recess, a partition inset 50 from the outer edge of said head and provided with an aperture communicating with said recess whereby a sample strip may be inserted into said recess, said head being provided with a slit to receive an end of 55 said sample strip therethrough, and a card detachably fastened to said partition and normally closing said aperture, said card being adapted to receive certain data relative to the fabric on said board and being 60 inset from the edges of said head to prevent damage thereto during the handling of the board.

In testimony whereof, I hereunto affix my signature.

JOHN R. SMITH.
